ASSORTING DEVICE

Moses Shuman, Los Angeles, Calif.

Application October 12, 1942, Serial No. 461,653

7 Claims. (CL 209—102)

This invention relates to devices for assorting various articles, such as screws, bolts, rivets and the like.

It is the general object of my invention to provide a simple, inexpensive and highly efficient device into which such screws, bolts or rivets, unassorted as to length, may be fed manually or automatically to be therein assorted and deposited into a series of receptacles, each of which is positioned to receive only articles of a predetermined length.

To this end, the invention resides in the combinations hereinafter described in detail and illustrated in the appended drawing, of which:

Fig. 1 is a plan view of a screw assorting device embodying the invention;

Fig. 2 is an enlarged end elevation of the device taken substantially on a line 2—2 of Fig. 1 as viewed in the direction of the arrow; and

Figs. 3 and 4 illustrate details of construction the importance of which will be appreciated upon perusal of the following detailed description.

The device of the invention, in the form illustrated in the drawing, comprises a base 1, which may be the floor on which the device is mounted. In standards 2 and 3 are journaled parallel shafts 4, 5, to which are rigidly secured pulleys 6, 7. An endless belt 8 is held suspended between these two pulleys. The standards are shown extended to form bearings for vertical shafts 10, 11, which carry pulleys 12, 13, and the latter are shaped to support an endless belt 14. Bevel gears 15, 16 are shown secured to the shafts 5 and 11 for the purpose of driving the two belts at exactly the same speed and so that the adjacent reaches 8^a, 14^a of the belts move in the direction of the arrow of Fig. 1. For this reason, it is ordinarily found most economical to make the four pulleys and the two belts exactly alike.

It is important to note, however, that the two belts are not arranged in parallel relation to each other, but that they gradually draw away from each other so as to provide therebetween a narrow, uniformly widening space. A continuous row of receptacles 17 is placed directly below this widening space to receive the assorted articles which, in the present instance take the form of flat head machine screws A. But, as above stated, the device operates equally well on bolts, rivets and the like. Examination of Fig. 1 will show that the articles advance on the belts until their pointed end slips over the edge of the belt 8 to drop into the proper receptacle.

Attention is now directed to Fig. 4, in which a screw or bolt B is shown riding on the adjacent

edges of the two belts. It is important to note that the upper edge of the vertical belt is placed a short distance above the surface of the horizontal belt. This has the advantage of tipping the point of the advancing article B downward so that the weight thereof will tend to maintain the head of the article in contact with the vertical belt. The gradual movement of the horizontal belt away from the latter further assists in maintaining the screw head in contact with the vertical belt. If the upper surface of the former is placed level with the upper edge of the latter, danger is present that the article, due to vibration or the like, may commence to roll while being carried forward and to drop over the edge of the vertical belt, thereby to defeat the purpose of the invention.

Where, as in Fig. 4, the underside of the screw head is square with the shank thereof, the device 20 will always function perfectly. But where articles like the flat head screw A are fed to the device there may be danger, where the angle of the underside of the screwhead approximates the horizontal, of the screw commencing to roll off the vertical belt and to drop prematurely. In order to eliminate all chance of such occurrence, it may be found advisable slightly to roughen or indent the upper edge of the vertical belt. To illustrate this feature, the edge of the belt 20 is, 30 in Fig. 3, shown made with corrugation-like notches 20^a, in which unassorted articles of different diameters may firmly lodge so that they cannot roll.

The drawing is merely illustrative of a preferred form of the invention and is not to be considered correctly proportioned, it being my sole aim clearly to indicate the principle of operation of the invention. Nor do I mean to limit myself to the identical structure or arrangement shown, but reserve the right to embody modifications within the scope of the claims hereto appended.

I claim:

45 1. A device for assorting screws and the like as to length comprising, a belt having a horizontal reach, a second belt having a vertically disposed reach adjacent one edge of said horizontal belt and spaced beyond said edge to one side of a vertical projection of the horizontal reach, the belts being so related that screws may be placed on the horizontal belt with their heads riding on and at least a portion thereof overhanging the upper edge of the vertical belt, the said upper edge being slightly elevated above the horizontal

reach so as to tilt the screws toward the latter thereby by gravity to maintain the heads of the screws riding on said upper edge, means for moving said reaches in the same direction at the same speed to carry the screws placed thereon along therewith, the reaches gradually diverging laterally so as to draw the point of each screw toward and over the edge of said horizontal reach.

2. Two belts extending along parallel planes, one belt having a horizontal reach, the other belt having a vertically disposed reach adjacent to and laterally spaced away from said horizontal reach and with its top edge preferably slightly above said horizontal reach, the two reaches being closer together at one end and gradually diverging laterally, and means for moving said two reaches in the same direction and at the same speed.

3. In a device for assorting screws and the like as to length, an endless belt having the surface of one reach thereof horizontally disposed, a second endless belt having the surface of one reach thereof vertically disposed adjacent to and laterally spaced apart from one side edge of said first named belt reach, the surface of said vertical reach gradually diverging laterally from the adjacent edge of the horizontal belt reach, the upper edge of said vertical reach taking a position slightly above and parallel with the upper surface of said horizontal reach, and means for moving said belt reaches in the same direction and at the same speed.

4. In a device for assorting screws and the like as to length, an endless belt having the surface of one reach thereof horizontally disposed, a second endless belt having the surface of one reach thereof vertically disposed adjacent to and laterally so spaced apart from one side edge of said horizontal belt reach that screws may be placed on the belts with their heads resting on the upper edge of said vertical reach and their points on said horizontal reach, means for moving both belt reaches in the same direction at the same speed, the surface of said vertical reach gradually diverging laterally from the adjacent edge of the horizontal reach so as to draw the point of each screw toward and over the edge of the horizontal reach.

5. In a device for assorting screws and the like as to length, an endless belt having the surface of one reach thereof horizontally disposed, a second endless belt having the surface of one reach

thereof vertically disposed adjacent to and laterally so spaced apart from one side edge of said horizontally disposed belt reach that screws may be placed on the belts with their heads resting on the upper edge of said vertically disposed reach and their points on said horizontal reach, the upper edge of said vertical reach taking a position slightly above and parallel with the surface of said horizontal reach so as to support the screws in slightly tilted position, thereby to prevent the screw heads from rolling off said upper edge, the said reaches gradually diverging laterally so as to draw the point of each screw toward and over the edge of the horizontal reach.

15 6. In a device for assorting screws and the like as to length, an endless belt having the surface of one reach thereof horizontally disposed, a second endless belt having the surface of one reach thereof vertically disposed adjacent to and laterally so spaced apart therefrom that screws may be placed on the belts with their heads resting on the upper edge of said vertically disposed reach and their points on said horizontal reach, there being notches in the upper edge of said vertical reach for receiving the screw heads thereby to prevent the screws from rolling off this edge, means for moving both belt reaches in the same direction at the same speed, the surface of said vertically disposed reach gradually diverging laterally from the adjacent edge of the horizontal reach so as to draw the point of each screw toward and over the edge of said horizontal reach.

7. In a device for assorting screws and the like as to length, a belt having a horizontal reach, a second belt having a vertically disposed reach adjacent one edge of said horizontal belt and spaced beyond said edge to one side of a vertical projection of the horizontal reach, the belts being so related that screws may be placed on the horizontal belt with their heads riding on and at least a portion thereof overhanging the upper edge of the vertical belt, there being notches in the upper edge of the vertical belt for receiving the screw heads thereby to prevent the screws from rolling off this upper edge, means for moving said reaches in the same direction at the same speed to carry screws placed thereon along therewith, the reaches gradually diverging laterally so as to draw the point of each screw toward and over the edge of said horizontal reach.

MOSES SHUMAN.
